12 Claims. (Cl. 164—283)

This invention relates generally to the continuous casting of metal and more particularly to a cooling system for cooling a casting wheel which is used in the continuous casting of metal.

The casting of metal in a peripheral groove around a rotating wheel, the groove being closed by an endless belt encircling a portion thereof, is well known in the casting art. One of the critical problems involved with this type of casting is the uniform cooling of the liquid metal while confined within the casting groove. Generally, two methods of cooling have been used on this type casting wheel: spray cooling and channel cooling.

Spray cooling has provided an easily controllable means for cooling the metal within the groove of an annular casting ring; however, this type of cooling has several drawbacks. One of its drawbacks is that, since the spray is made to impinge at spaced intervals on the outside surface of the casting ring, the casting ring must be made as thin as possible in order to provide the best conduction of heat therethrough. This particular construction, however, results in greatly reduced strength of the annular casting ring, thereby allowing the metal of the casting ring to be easily deformed under the extremely high temperatures to which it is subjected. Another drawback is that cooling has been non-uniform because the heat transferred is greatest at the points of impingement of the stream of coolant against the casting ring, since at these positions the coolant is in contact with the casting ring. It is readily understood that, as points on the ring move between positions where coolant sprays are located, less coolant is in contact with the ring. This has caused hot and cold spots along the casting ring which results in inefficient cooling.

Channel cooling of annular casting rings has usually been done with arcuately extending channels formed inwardly of the periphery of a casting ring, and adjacent to a casting groove. This has required that the casting ring be made of relatively thick wall sections in order to provide the necessary strength for proper support of the metal within the casting groove, and has also resulted in non-uniform cooling of the metal bar formed within the casting ring. In usual practice, the coolant is relatively cool when first introduced into the coolant channels, but as the coolant flows along the circular path of the coolant channels it picks up heat dissipated from the molten metal that is confined within the casting ring. As the coolant is heated, the heat transfer rate decreases due to the decrease in temperature difference; and, the liquid coolant thereby produces a varying cooling rate at different points along the length of the coolant channel. Therefore, even if several short lengths of cooling channels were used around the casting ring, the cooling rate would vary along the length of each cooling channel.

The present invention overcomes these and other problems associated with previous cooling systems for casting rings by providing a plurality of radially extending channels which allow substantially uniform cooling of the casting ring along the length of the casting groove at all times. The cooling system of the present invention possesses the advantages of:

(1) Uniform cooling along segments of the length of cast metal since the coolant is introduced at closely spaced intervals positioned on radii of the casting ring

2

thereby producing more total coolant ring contact time in a given zone;

(2) Minimizing the path of travel of each individual coolant channel, thereby producing a maximum heat transfer differential at each position of coolant introduction; and,

(3) Flexibility in controlling the rate of coolant flow to establish staged cooling zones.

The apparatus of the invention comprises a casting ring having radially extending coolant channels formed therein so that the coolant contacts the casting ring at a relatively short distance from the outer surface of the casting groove as the coolant is caused to flow through the radially extending channels in the casting ring, and along a very small increment of the length of the groove. Coolant is introduced into the channels by a plurality of radially extending nozzles disposed adjacent the inner surface of the casting ring which also force coolant along the radially extending sectional channels. The particular arrangement of the nozzles can be easily varied so that different uniform rates of cooling can be produced in different zones of the casting ring if that should be desired.

These and other features and advantages of the present invention will become apparent from consideration of the following detailed description taken in conjunction with the accompanying drawings wherein like characters of reference designate corresponding parts throughout and in which:

FIG. 1 is an elevational view of a casting machine utilizing an embodiment of the invention;

FIG. 2 is a cross-sectional view of a casting ring embodying the invention;

FIG. 3 is a cross-sectional view of the casting ring shown in FIG. 2, removed from its associated structure;

FIG. 4 is a cross-sectional view of a second embodiment of the present invention;

FIG. 5 is an enlarged sectional view of a portion of the second embodiment of the invention shown in FIG. 4, partially broken away to illustrate the position of the cooling channels within the casting ring;

FIG. 6 is a schematic illustration showing a cooling manifold and nozzle arrangement for zoned cooling that can be utilized in the present invention; and

FIG. 7 shows a means for rotating the cooling manifold shown in FIG. 4.

Referring now particularly to the detailed drawings, it will be seen that FIG. 1 illustrates a casting machine in which the invention is embodied. It is to be understood, however, that the invention is not limited in any way by the details disclosed herein since it may be embodied in other equivalent forms.

The casting machine has a casting wheel 10, a frame 11 rotatably supporting the casting wheel 10 and an endless belt 12 encircling a portion of the casting wheel 10. The periphery of the casting wheel 10 carries the casting ring 14 wherein the invention is embodied.

Referring to FIGS. 2 and 3, the first embodiment of the invention is seen to comprise a disc shaped mounting plate 15 which is integral with, and extends perpendicularly outward from a support shaft 13, the shaft 13 being rotatably journaled in a frame 11. A retaining annulus 18 has the same diameter as the support plate 15 and is spaced from the support plate 15 so that their axes of rotation coincide. An annular casting ring 14 is retained between the support plate 15 and the annulus 18 in appropriate annular slots 19 which are formed in the inner faces of the support plate 15 and the annulus 18. A plurality of bolts 16 extend through the support plate 15, the casting ring 14 and the annulus 18 to hold the assembly together to form the casting wheel 10.

The casting ring 14 defines a casting groove 20 in its outer peripheral surface 20a, and has transverse, outwardly extending lips 21 adjacent the mouth of the groove 20, the lips 21 being received by the slots 19 that are provided in the support plate 15 and the annulus 18. Two narrow coolant channels 24 extend radially inwardly from beneath the lips 12 of the casting ring 14 adjacent the inner surface 20a of the casting groove 20, and converge at a point along a radius of the casting ring 14 where the coolant is introduced. A plurality of these channels 24 are formed at closely spaced intervals about the circumference of the casting ring 14. The outer ends of the coolant channels 24 terminate immediately below the outwardly extending lips 21 of the casting ring 14; and, the coolant is returned inwardly through the return channels 25 which communicate with the channels 24. This allows coolant to be introduced into the cooling channels 24, to flow along the channels 24 adjacent the casting groove 20 while removing heat conducted from the molten metal through the casting ring 14, and to exit inwardly toward the center of the casting wheel 10 along the channels 25. It is to be understood that, in order for the casting ring 14 to retain its proper strength, the channels 24 must have a narrow width and be spaced far enough apart so that support webs 24 between the channels 24 provide enough strength to keep the casting ring 14 from warping or otherwise deteriorating when hot, molten metal is poured within the casting groove 20.

Referring to FIGS. 4 and 5, the second embodiment of the invention is seen to comprise a disc shaped mounting plate 15' integral with and extending perpendicularly outward from a support shaft 13'. A retaining annulus 18' has the same diameter as the support plate 15' and is spaced from the support plate 15' so that their axes of rotation coincide. A U-shaped, removable mold portion 26 is retained between the support plate 15' and the annulus 18' in appropriate annular slots 19' which are formed in the inner faces of the support plate 15' and the annulus 18'. A support member 28 is also carried between the support plate 15' and the annulus 18' by bolts 16', and serves to support the removable mold portion 26. The entire wheel assembly 10 is rotatably carried by a frame 11' in which the support shaft 13' is journaled.

The removable mold member 26 defines a casting groove 20, and has lateral, outwardly extending lips 21' adjacent the mouth of the groove 20', the lips being received by the slots 19' provided in the support plate 15' and the annulus 18'. A plurality of set screws 23 serves to retain the lips 21' of the removable mold portion 26 in the slots 19'.

The support member 28 is mounted so that its outside surface is continuous with the inside surface of the removable mold portion 26 by providing a recess 27 in which the removable portion 26 rests. The support member 28 comprises two mating sections 28a and 28b so that the support member 28 can be assembled around the base portion of the removable mold portion 26. For the sake of simplicity however, in the following description of the support member 28, it will be referred to as a single element. The removable mold portion 26 has coolant channels 44, each of which is formed inwardly of the recess 27 along a given radius of the support member 28 and opens into the recess 27. A plurality of these channels 44 are formed at closely spaced intervals about the circumference of the support member 28. An inlet port 45 extends inwardly of the innermost point of each of the channels 44, through the support member 28, and opens on the inner surface of the support member 28; therefore, coolant can be introduced into the channels 44 and flow radially outward, while remaining in contact at all times with the inside surface of mold portion 26. Return channels 30 extend radially inward from the outermost extending ends of the channels 44.

Several forms for supplying coolant to the channels 44 can be used, three of such forms being shown herein

in FIGS. 4, 6 and 7; and, all include means within the cavity defined by the support plate 15', the annulus 18' and the support ring 28 of the second embodiment of the invention.

Referring to FIGS. 4 and 5, a first form of coolant introductory means is shown which comprises a coolant manifold 32 having outwardly extending nozzles 34 aligned with the ports 45 in the support member 28 for spraying coolant into the channels 44. The coolant manifold 32 communicates with a coolant supply pipe 35 which has a valve 36 therein for regulating the flow of coolant through the pipe 35, the manifold 32 and hence the channels 44 in the support member 28. Therefore, regulating the valve 36 will vary the flow of coolant through the channels 44, hence the rate of heat transferred from any metal that may be within the casting groove 20.

Referring now to FIG. 6, a second form of introductory means is shown providing zoned cooling. The only necessary changes in the first embodiment of the introductory means are in the coolant manifold 32 which is shown as a coolant manifold 32' in FIG. 6. Any number of cooling zones can be provided in the introductory means, but only three such cooling zones A, B and C are shown in the embodiment of FIG. 6. The coolant manifold 32' is stationary within the cavity formed in the wheel assembly, with a first zone A having a plurality of closely spaced nozzles 34' extending from the coolant manifold 32' so as to introduce a large volume of coolant into the channels 44. As is shown in FIG. 6, the zone A is usually placed adjacent to support ring 28, beginning at that point of the mold portion 26 which receives the liquid metal. A second zone B is provided by a plurality of nozzles 34', which are spaced a greater distance apart than those nozzles 34' in zone A. As seen in FIG. 6, the cooling zone B is spaced clockwise from, and adjacent to, zone A. These nozzles 34' of zone B are usually spaced a distance further apart than those of zone A, since the metal is substantially solid by the time it passes through zone A, and less heat transfer is needed. Zone B usually extends clockwise around the manifold 32' to that point on the mold portion 26 at which the solidified metal bar is extracted from the casting groove 20. Extending from the end of zone B, clockwise around the manifold 32' to the beginning of zone A, is the cooling zone C which is provided by a plurality of nozzles 34', the nozzles 34' being spaced a greater distance apart than either those of zone A or those of zone B. Since the solidified metal bar has been extracted from the casting groove during the time the support member 28 is adjacent the cooling zone C, less flow of coolant is needed than in zones A and B since the casting groove is open and free from contact with the molten metal. Thus, it is seen that zone A provides the greatest cooling capacity for the liquid metal, zone B provides a lesser cooling capacity than zone A, and zone C provides the least cooling capacity of the three zones A, B and C. It will be further seen that more or fewer cooling zones can be provided by the nozzles 34' as required to solidify the liquid metal injected into the casting groove 20 and to cool this solidified bar to a desired temperature before the bar is extracted from the casting groove 20.

Referring now to FIG. 7, a third embodiment of the introductory means is shown. This embodiment uses an independently rotatable manifold 32''. The coolant manifold 32'' has the same general construction as the coolant manifold 32, but is rotatably journaled in a support stand 40 so that the manifold 32'' can be rotated in the direction of rotation of the casting wheel 10, or in the opposite direction of rotation from the casting wheel 10. A coupling 42 is provided at the end of a support tube 43 so that water can be introduced into the coolant manifold 32'' via the support tube 43. The flow of coolant in this third form of the introductory means is controlled by the valve 36 as shown in FIG. 1. With this form, a more nearly uniform flow of coolant will be introduced against the outside surface of the removable mold portion 26

through the channels 44 since the optimum speed relationship can be achieved by rotating the manifold 32" in the proper direction and speed no matter what the rotational speed of the wheel 10 may be. This optimum speed relationship is that speed relationship at which maximum cooling efficiency takes place; therefore, the maximum cooling efficiency can be achieved regardless of the rotational speed of the support ring 28.

It will be obvious to those skilled in the art that many variations can be made in the embodiments herein chosen for illustration without departing from the scope of the invention as defined by the appended claims.

I claim:

1. In a casting machine, a casting ring having in its peripheral surface a casting groove and having formed therein a plurality of separate first channels each of which extends adjacent said casting groove from inwardly of said casting groove substantially to said peripheral surface and each of which is along its length substantially equi-distant from said casting groove, means for positioning said casting ring for rotation about an axis and for providing with said casting ring a plurality of second channels each of which is continuous with one of said first channels and extends inwardly toward said axis, and means positioned inwardly of said casting groove for flowing coolant through said first channels and said second channels.

2. The casting machine of claim 1 in which each of said first channels extends radially outward toward said peripheral surface.

3. The casting machine of claim 2 in which each of said second channels extends radially inward away from said peripheral surface.

4. The casting machine of claim 1 in which said means positioned inwardly of said casting groove includes a plurality of ports in said casting ring continuous with said first channels, a plurality of nozzles adjacent said ports, and means for providing said coolant to said nozzles.

5. The casting machine of claim 4 in which said ports move relative to said nozzles.

6. The casting machine of claim 4 in which said nozzles are spaced along the inner periphery of said casting ring.

7. The casting machine of claim 6 in which the spacing between said nozzles varies.

8. The casting machine of claim 1 in which said casting ring includes a support member having a recess and a mold portion defining said casting groove positioned in said recess.

9. The casting machine of claim 8 in which said first channels are formed between said support member and said mold portion.

10. The casting machine of claim 8 in which said support member includes separable mating sections having said mold portion positioned between them.

11. In a casting machine having an annular mold portion rotatable about an axis, a cooling system comprising an annular support member shaped to receive said mold portion and having a plurality of radially extending channels therein opening against said mold portion so that coolant flowing through each of said channels is confined on one side by said support member and on the other side by said mold portion, means for introducing coolant into said channels, said means comprising a circular coolant manifold rotatable about said axis of said mold portion independently of said mold portion and having outwardly extending nozzles around the periphery thereof, and valve means for judiciously regulating the flow of coolant through said nozzles.

12. In a casting machine having an annular mold portion rotatable about an axis, a cooling system comprising an annular support member shaped to receive said mold portion and having a plurality of radially extending channels therein opening against said mold portion so that coolant flowing through each of said channels is confined on one side by said support member and on the other side by said mold portion, and means for introducing coolant into said channel comprising a circular coolant manifold rotatable about said axis of said mold portion independently of said mold portion and having a plurality of equally-spaced coolant-discharging nozzles around the periphery thereof disposed adjacent entrances of said channels, and driving means for rotating said coolant manifold.
